UNITED STATES PATENT OFFICE.

EDWARD C. DE YARMETT AND EDWARD M. HAYNES, OF HAMPTON,
VIRGINIA.

WATER-TUBE BOILER.

SPECIFICATION forming part of Letters Patent No. 633,575, dated September 26, 1899.

Application filed July 17, 1899. Serial No. 724,164. (No model.)

To all whom it may concern:

Be it known that we, EDWARD C. DE YARMETT and EDWARD M. HAYNES, citizens of the United States, residing at Hampton, in the county of Elizabeth City, State of Virginia, have invented certain new and useful Improvements in Water-Tube Boilers, of which the following is a specification.

This invention relates to improvements in water-tube boilers, and has for its object to provide a novel arrangement of tubes whereby the water is delivered to the steam-drum in a thoroughly-heated condition and an efficient and satisfactory circulation maintained. These objects are accomplished by a novel arrangement of tubes in a number of series crossing each other above the fire-grate, disposed so as to obtain the greatest possible heating of the water within a given space, and a novel arrangement of the tubes in each series by which those tubes which are the most exposed to the heat of the fire deliver into the upper portion of the steam-drum and those which are the least exposed to the fire heat leave the drum at its lower portion, whereby they serve the purpose of conducting the cooler water from the drum, and thus accomplish an efficient and satisfactory circulation.

The invention has also for its object to otherwise improve in construction and arrangement boilers of the class to which it relates.

To these ends said invention consists in the novel arrangement and mode of operation of parts hereinafter described, and pointed out in the claims, reference being made to the accompanying drawings, in which—

Figure 1 is a cross-sectional view of the boiler; and Fig. 2 a side elevation, in which the casing-boiler is omitted and part of the feed-water-heating pipes broken away.

In the said drawings the reference-numeral 3 indicates the boiler-casing, having a stack 4 for conducting away the products of combustion. Water or mud drums 5 are arranged longitudinally of the casing near the bottom

and at opposite sides thereof. Feed-water heaters 6 are arranged at opposite sides of the boiler-casing and slightly separated from such casing. These feed-water heaters are in the form of manifolds and practically cover the side walls of the casing to a point about on a level with the steam-drum, so that they receive the direct heat of the fire, and in addition to providing the initial heat for the feed-water serve as a water-jacket to protect the sides of the casing from the flames.

Between the water or mud drums 5 is located a fire-grate 7, and above the latter and in the upper portion of the casing the steam-drum 8 is located.

Communicating at their lower ends with the water or mud drums 5 and at their upper ends with the steam-drum are a number of series of water-tubes 9 and 10, arranged longitudinally of the drum in series and which are approximately in the form of ogee curves, which admit of free expansion and contraction without injurious strain. The curves described by these tubes are easy, so that they are susceptible of being cleaned without difficulty.

The series of tubes cross each other above the fire grate 7, those series which communicate with the water or mud drum 5 at the left of the casing crossing over and communicating with the steam-drum at the right-hand side and those series which communicate with the right-hand water or mud drum 5 crossing over and communicating with the steam-drum at the left-hand side thereof, so that they form a bridge or baffle over the fire, and this arrangement results in deflecting the flame and heat-waves of the fire, causing the same to pursue different paths, as indicated by the arrows in Fig. 1 of the drawings. It will be seen that the series of tubes 9 baffle and deflect the flame and heat-waves, compelling one portion to pass over the series of tubes 10, after which they pass over several of the longer tubes *a b c* in the series 9 above the place of crossing and imparting

heat thereto, while the series of tubes 10 cause the motion of the flames and heat-waves to likewise cross over the surface of the series of tubes 9 and over the surfaces of several of the longer tubes $a' b' c'$ in the series 10 above the point of crossing, imparting a second supply of heat thereto, and in the example shown in the drawings the upper extremities of the outermost or longer tubes 10 $a b a' b'$ in each series, which each discharge at the higher points into the steam-drum, receive the flames and heat-waves a third time, whereby these tubes are more thoroughly heated than the others in the series. The 15 shorter tubes $d e$ and $d' e'$ in each series, which are farthest from the fire and communicate with the lowermost portion of the steam-drum, it will be seen, are traversed by the flames and heat-waves but once and below the point 20 of crossing of the series 9 and 10, their upper portions being out of the lines or paths pursued by the heat because of the deflection of baffling hereinbefore referred to, and these tubes are manifestly heated to a considerably 25 less degree than those with which the heat comes in contact a plurality of times. This arrangement is valuable, since it will be seen the longer tubes, which are subjected to influence of the heat most, discharge into the 30 drum at greater elevations than the short tubes, which are exposed to the heat but once, and thus an efficient and satisfactory circulation is maintained, the hottest water being 35 discharged into the uppermost part of the steam-drum and the cooler water in said drum being conveyed back to the water or mud drums through the short tubes, which have a temperature very much less than the longer tubes, as above explained. It has been found 40 that in those tubes which are subjected to the heat several times, as set forth, the water is heated so intensely that steam is formed in the tubes during the course of the water toward the steam-drum, while in the shorter 45 tubes, which are subjected to the heat but once, the cooler water from the steam-drum descends very satisfactorily to the water or mud drums, thus maintaining a perfect circulation without the necessity of auxiliary 50 circulation-pipes.

By our invention we provide a water-tube boiler in which, by reason of the novel arrangement and formation of the tubes, the greatest amount of exposure of the heating 55 surface of the pipes to the heat is obtained in a casing of given dimensions, and at the same time an efficient and satisfactory circulation is maintained by arranging those tubes in each series which communicate with the low- 60 ermost portion of the steam-drum and conduct the cooler water therefrom so that they are subjected to the heat in lesser degree and have therefore a materially less temperature

than those tubes which are arranged in the most intense heating-zone of the fire and are 65 several times traversed by the heat, and which serve to thoroughly heat and deliver the water to the drum at higher points thereof.

Having thus described the invention, that which is claimed as new is—

1. In a water-tube boiler, the combination with water-drums, and a steam-drum, of a plurality of series of water-tubes communicating with said water-drums and with opposite sides of the steam-drum and crossing each 70 other over the fire-grate to form a bridge, the shorter tubes of each series being arranged farthest from the more intense heat zone of the fire and leading from the lower portion of the steam-drum and the other tubes communicating with the upper portion of the steam-drum, substantially as described.

2. In a water-tube boiler, the combination with water-drums, a steam-drum, and a fire-grate, of a plurality of series of water-tubes 85 communicating with said water-drum and with opposite sides of the steam-drum, crossing each other over the fire-grate, and the shorter tubes thereof arranged farthest from the fire-grate and communicating with the 90 lower portion of the steam-drum, and the other tubes communicating with the upper portion of the steam-drum, substantially as described.

3. In a water-tube boiler, the combination 95 with water-drums, a fire-grate, and a steam-drum, of water-tubes communicating with said water-drums and steam-drum and crossing each other over the fire, the tubes being arranged so that some of the tubes in each 100 series are subjected to the influence of the heat a plurality of times, and others of said tubes are subjected to the heat but a single time, substantially as described.

4. In a water-tube boiler, the combination 105 of water-drums arranged at opposite sides of the casing, feed-water heaters communicating with said water-drums and protecting and forming a water-jacket for the side walls of the casing, a fire-grate arranged between said 110 water-drums, a steam-drum located above said grate, and water-tubes communicating with said water-drums and steam-drum, crossing each other above the fire-grate and communicating with the steam-drum at opposite 115 sides thereof those pipes of each series which are most remote from the greatest heating zone of the fire leading from the lower portion of the steam-drum, and those which are arranged in the more intense heating-zone discharging into the higher points of the steam-drum, substantially as described.

5. In a water-tube boiler, the combination of water-drums arranged at opposite sides of the casing, a fire-grate arranged between said 120 water-drums, a steam-drum located above

said grate, and water-tubes communicating with said water-drums and steam-drum, crossing each other above the fire-grate and communicating with the steam-drum at opposite 5 sides thereof those pipes of each series which are most remote from the greatest heating zone of the fire leading from the lower portion of the steam-drum, and those which are arranged in the more intense heating zone 10 discharging into the higher points of the steam-drum, substantially as described.

In testimony whereof we have hereunto set

our hands in presence of two subscribing witnesses.
